UNITED STATES PATENT OFFICE.

VINCENZO PAONE, OF UTICA, NEW YORK.

RADIATOR.

Application filed November 9, 1925. Serial No. 67,885.

The invention relates to improvements in radiators of the type used upon automobiles, tractors, etc. Ordinarily, the water vapor or steam which rises to the upper portion of the radiator, escapes through the overflow pipe and is discharged to the atmosphere, with the result that the water supply must be replenished from time to time. To overcome this difficulty, it has heretofore been proposed to make use of a condenser in connection with the radiator, to convert the vapor into water and return the latter to the radiator. In so far as I am advised, condensers of the types heretofore provided for this purpose, have been bulky or unsightly and hence have not come into practical use. It is the object of my invention however, to provide a radiator in which a condenser is embodied in the usual core, through which the water circulates.

In carrying out the above end, a further aim is to utilize one of the conventional water-circulating passages of the radiator core, as a part of a communicating passage between the upper portion of the radiator and the condensing chamber.

With the foregoing and minor objects in view, the invention resides in the novel subject matter hereinafter described and claimed, the description being supplemented by the accompanying drawing.

Figure 1 is a rear elevation of a radiator constructed in accordance with my invention.

Figures 2 and 3 are horizontal sectional views as indicated by lines 2-2 and 3-3 of Fig. 1.

Figure 4 is a vertical sectional view as disclosed by line 4-4 of Fig. 2.

Figure 5 is a vertical sectional view at right angles to Fig. 4, as indicated by line 5-5 of Fig. 1.

Figure 6 is a detail view partly in section and partly in elevation, disclosing a different form of construction.

Figure 7 is a sectional view partly in elevation showing another form of construction.

A radiator is shown comprising upper and lower headers U and L respectively, said headers being connected by a water circulating core C which is shown of cellular form, but may instead embody a plurality of water circulating tubes, or may be of any other known or desired form. The upper header is provided with the usual filling neck

N closed by the cap F. The headers are provided with the usual hose connections H.

The radiator is so constructed that a recess 7 is formed in the core C, said recess preferably opening through the rear and through one vertical edge of said core and extending from the upper to the lower header. In this recess, I solder or otherwise secure a condensing tank 8, the upper end of said tank being provided with an air vent 9 preferably in the form of a tube, as shown. A passage is provided, establishing communication between the lower end of the tank 8 and the header U, at a point above the water level and preferably within the neck N. Probably the most simple form of this passage is disclosed in Fig. 6, in the form of a tube 10. The construction however, which will probably be desired in most instances, is illustrated in the remaining views. A pipe 11, preferably located within the header U is connected with the upper end of one of the water circulating channels W of the core C, said pipe having its upper end disposed above the water level of the header U, said end being by preference located within the neck N. Connected with the lower end portion of the channel W, is another pipe 12 which establishes communication between said channel and the lower end of the tank 8. The upper and lower ends of the channel W are closed by solder 13 or in some other adequate manner, so that they do not directly communicate with the water-containing portions of the headers U and L, and consequently, said channel cannot perform its usual function but is assigned the duty of forming part of a communicating passage between the lower end of the tank and the upper portion of the radiator.

In either form of the invention, as water vapor ascends into the upper portion of the radiator, and pressure within the latter increases, such vapor will be conducted to the tank 8, in which it condenses, and whenever the radiator cools sufficiently, more or less of a vacuum will be created, within its upper portion and this vacuum serves to draw the accumulated condensate from the tank back into the header U. It will thus be seen that water is conserved which is ordinarily lost and hence that the supply need not be so frequently replenished. The tube 9 not only acts as a safety outlet for the cooling system of the machine, but air may escape through this tube as the water

rises in the tank 8, and may re-enter the tank as the water is returned to the radiator proper. The only means of communication between the atmosphere and the interior of a cooling system embodying the improved radiator, is by means of the tube 9, when the cap F is in place and the system is in operation.

In Fig. 7, a condensing tank 8^a is embodied in a radiator structure and is located under the lower water header. A communicating passage between the tank 8^a and the upper end of the radiator, is formed in part by one of the usual water circulating channels W', a tube 11^a being connected to the upper end of this channel while a tube 12^a is connected to the lower end thereof, the tube 11^a extending into the filling neck of a radiator while the tube 12^a extends into the tank 8^a. At 9^a, a combined vent and emergency overflow, is provided for the tank 8^a.

It will be seen from the foregoing that I have provided a rather simple and inexpensive, yet a distinct advance in the art of radiator condensers, and while the details disclosed are preferably followed, I wish it understood that the present showing is for illustrative purposes only, and that within the scope of the invention as claimed, numerous variations may be made.

I claim:

1. In a liquid cooling radiator having upper and lower headers and a liquid circulating core provided with liquid channels, a condensing chamber embodied in said core for condensing vapor from the upper portion of the radiator, said chamber having a combined vapor inlet and liquid return passage establishing communication between its lower end and a high point of the radiator, and including one of the liquid channels of the core, said channel being sealed at its lower end against conducting water from one header to the other, said chamber being provided with an air vent.

2. A liquid cooling radiator comprising upper and lower headers, a water circulating core connecting said headers and having

liquid channels and a recess, a vapor condensing tank inset in said recess and having an air vent at its upper end, a passage connected to the upper end of one of the liquid channels of said core and having an open end in the upper header above the liquid level, and a second passage connecting the lower end of said channel with the lower end of said tank, said channel being sealed against conducting water from one header to the other to prevent it from performing its usual function.

3. In a liquid cooling radiator, a liquid circulating core having liquid channels, a condensing tank embodied in the radiator structure, and a combined vapor inlet and liquid return passage establishing communication between said tank and a portion of the radiator above the water level, a portion of said passage being formed by one of said water circulating channels of the radiator, said tank also having an air vent.

4. A water cooling radiator including water circulating channels and an upper and lower header with a condensing chamber located in said radiator between said headers, a communicating passage between the upper portion of the top header and the lower portion of said chamber, said passage being formed in part by one of the water circulating channels of the radiator.

5. In a liquid cooling means having upper and lower headers and a liquid circulating core provided with liquid channels, a condensing chamber for condensing vapor from the upper portion of the upper header, said chamber having a combined vapor inlet and liquid return passage establishing communication between said chamber and a high point of the upper header and embodying one of the liquid channels of the core, and an extension extending to said high point, said one channel being sealed at its lower end against conducting water from one header to the other, said chamber being provided with an air vent.

In testimony whereof I have hereunto affixed my signature.

VINCENZO PAONE.
